PAINTING APPLIANCE OF THE DETACHABLE ROLLING SLEEVE TYPE

Earl E. Thomas, Detroit, Mich.

Application August 14, 1950, Serial No. 179,149

6 Claims. (Cl. 29—116)

1

This invention relates to painting appliances of the type equipped with a detachable rotatable sleeve from which paint may be applied to a work surface by rolling the sleeve along such surface. The invention may be considered an improvement on the subject matter of my United States Patent No. 2,520,863, issued August 29, 1950.

An object of the invention is to simplify and reduce the cost of a painting appliance employing a detachable rotatable paint-applying sleeve, by eliminating the usual expansible and contractible roller, and mounting said sleeve upon a pair of spaced heads journaled on the shaft of said appliance.

Another object is to equip said spaced heads with spring chucks suited to enter and be compressed by the end portions of the sleeve and to frictionally grip the sleeve by their expansive reaction.

Another object is to provide sleeve-mounting members carried by and bridged between said chucks.

Another object is to adapt one of said heads to form an end abutment for the sleeve.

Another object is to rotatably mount on the shaft of a painting appliance one or more elastic disks for frictionally retaining a paint-applying sleeve on such shaft.

These and various other objects are attained by the construction hereinafter described and illustrated in the accompanying drawings, wherein:

Fig. 1 is a front view, in partial section on the line 1—1 of Fig. 2 of my improved appliance, showing the detachable sleeve in use position on the appliance.

Fig. 2 is a top plan view of the same, omitting the sleeve.

Fig. 3 is an axial sectional view of the appliance in a modified form.

Fig. 4 is a cross sectional view of the modification, taken on the line 4—4 of Fig. 3.

Fig. 5 is an axial sectional view, in partial section, of a further modification.

Fig. 6 is a cross sectional view of the last-mentioned modification, taken on the line 6—6 of Fig. 5.

Fig. 7 is an axial sectional view of another modification of the appliance.

Fig. 8 is a cross section taken on the line 8—8 of Fig. 7.

Fig. 9 is a fragmentary axial sectional view of the appliance, employing another type of expander.

2

Fig. 10 is a cross sectional view, taken on the line 10—10 of Fig. 9.

Referring now in greater detail to the construction shown by Figs. 1 and 2, the reference character 1 designates a shaft formed by one end portion of a rod, whereof the other end portion forms a shank 2 inserted in a handle 3 disposed transversely to the shaft, said rod having a gooseneck portion 4 joining the shaft and shank. Rotatable on the shaft, at its free end is a circular head 5, preferably a sheet metal stamping, such head peripherally forming an annular flange 5a projecting toward the gooseneck end of the shaft. Said head is restrained from axial sliding, jointly by a collar 6 press-fitted on the shaft and by a headed screw 7 set into the shaft. Near its juncture with the gooseneck, the shaft journals a second sheet metal head 8 held from sliding by collars 9, and of a diameter somewhat exceeding that of the head 5. A pair of substantially U-shaped spring chucks 10 have their respective yoke portions 10a welded or otherwise fixed centrally on the respective heads 5 and 8, the jaws of each chuck projecting toward the companion chuck and having a slight relative divergency in so projecting. Detachably mounted on the two chucks and frictionally retained thereon is a sleeve comprising a quite stiff inner member 11 formed preferably of fibrous material, and an outer covering 12 having a suitable paint-retaining nap or pile. Lamb's wool or felt exemplify materials suited to form the outer covering. The members 11 and 12 are adhesively or otherwise permanently interconnected as a unit. The spacing of the free end portions of each pair of spring jaws 10 predeterminedly exceeds the outside diameter of the head 5, so that the sleeve 11, 12 may be freely slipped over said head and still effect a deflection of said jaws, adapting the latter to frictionally maintain the sleeve in place under any stresses normally arising in use of the appliance. The free ends of the spring jaws are bent slightly toward the shaft, as indicated at 10b, avoiding any tendency of such ends to resist sliding of the member 11. In its applied position, the inner end of the sleeve abuts the head 8, the two heads closing the sleeve ends and excluding paint from the sleeve interior.

The construction shown in Figs. 3 and 4 conforms to preceding description with exception that bridging strips 13 rigidly interconnect the legs of the two spring chucks 10c, the main length of said bridging strips being sufficiently spaced from the shaft to frictionally interiorly engage

the sleeve 11, 12 and mount the latter. Said strips are transversely arcuately curved to conform to said sleeve.

The modification appearing in Figs. 5 and 6, journals a pair of sheet metal heads 14 and 14a on the shaft, respectively adjacent its free end and its gooseneck connection, such heads having peripheral annular flanges projecting toward each other. Said heads are adapted to be slip-fitted in and form closures for the extremities of a sleeve 11, 12. Said sleeve is frictionally held in place by a pair of rubber or like resilient disks 15 rotative on the shaft and spaced from each other and from the heads 14 and 14a. As illustrated, sleeves 16 are loosely mounted on the shaft to exercise the desired spacer function.

The construction illustrated in Figs. 7 and 8 differs from that of Figs. 5 and 6 in that the disks 15 are each replaced by a rotatable chuck comprised of two cupped members 17 disposed back to back and formed with oppositely projecting peripheral jaws 18, which diverge slightly from the axis of the chucks in receding from the latter. The extremities of said jaws are inturned toward the shaft to have clearance from the sleeve 11, 12. Sleeves 19 and 19a hold the chucks properly spaced apart and from the heads 14' and 14a'.

Figs. 9 and 10 disclose a construction patterned after that of Figs. 5 and 6, except that the disks 15 of the latter figures are replaced by coiled wire springs 20, each comprising at least one convolution, and each having a radial end portion 21, looped centrally of the spring to rotatively mount the spring on the shaft.

The described construction, in its various forms, saves material and achieves increased lightness by using relatively small and compact spring chucks in place of the sheet metal rollers heretofore required as a mounting for the paint-applying sleeve.

What I claim is:

1. An appliance for painting and like operations, comprising a shaft having a free end, a sleeve detachably mounted on the shaft and formed by a stiff inner tube and a cover for such tube having a paint-retaining pile, a head journaled on the shaft substantially at its free end, forming a closure for the corresponding end of the sleeve and freely fitting within the sleeve, a second head journaled on the shaft remotely from said free end and endwise abutted by the sleeve, and a pair of spring chucks respectively carried by the respective heads and each having jaws inserted in and contracted by the sleeve and expansively reacting to frictionally grip the sleeve, the sleeve being manually slidable along its axis to engage it with and disengage it from the chucks.

2. An appliance for painting and like operations, comprising a shaft having a free end, a

sleeve detachably mounted on the shaft and formed by a stiff inner tube and a cover for such tube having a paint-retaining pile, a pair of heads journaled on the shaft, one substantially at its free end and the other remote from such end, said heads substantially closing the sleeve ends, and a pair of chucks respectively carried by the respective heads and each having spring jaws divergently projecting toward the other head and interiorly frictionally gripping the sleeve.

3. An appliance for painting and like operations, as set forth in claim 1, said jaws having ends remote from the corresponding ends bent toward the shaft to terminally clear the interior face of the sleeve.

4. An appliance for painting and like operations, comprising a shaft having a free end, a sleeve detachably mounted on the shaft and formed by a stiff inner tube and a paint-retaining cover for such tube, a pair of heads journaled on the shaft, one substantially at its free end and the other remote from such end, said heads substantially closing the sleeve ends, and a plurality of members secured to the mutually confronting faces of said heads and bridged between the heads and sprung outwardly from the shaft to interiorly frictionally grip the sleeve.

5. An appliance for painting and like operations, comprising a shaft having a free end, a sleeve detachably mounted on the shaft and formed by a stiff inner tube and a cover for such tube having a paint-retaining pile, a pair of heads journaled on the shaft, one substantially at its free end and the other remote from such end, said heads substantially closing the sleeve ends, and a pair of chucks fixed respectively upon the respective heads, each chuck having a plurality of spring arms projecting toward the other chuck, and means on said arms sprung by the arms into frictional interior engagement with said sleeve.

6. An appliance for painting and like operations, as set forth in claim 4, said bridging members being transversely curved to substantially conform to the sleeve.
